UNITED STATES PATENT OFFICE.

JOHN G. WELSH, OF SAN DIEGO, CALIFORNIA.

CRANKING DEVICE.

1,151,842.

Specification of Letters Patent. Patented Aug. 31, 1915.

Application filed October 27, 1913. Serial No. 767,555.

To all whom it may concern:

Be it known that I, JOHN G. WELSH, a citizen of the United States, residing at San Diego, in the county of San Diego and State of California, have invented certain new and useful Improvements in Cranking Devices, of which the following is a specification.

This invention relates to cranking mechanisms for hydro-carbon engines, and it has for one of its objects the provision of an improved device of this character in which the connection between the crank-operated member and the engine shaft will be interrupted or broken immediately upon the reverse rotary movement of the engine shaft due to back-firing.

The invention has, furthermore, for its object the provision of a device of this character which comprises a crank-operated member carrying a pawl which normally serves to engage the engine shaft and rotate the same as long as this rotation is in the same direction; but this pawl will be immediately disengaged from the shaft member upon the reversal of the rotary movement of the latter.

Further objects of the invention will hereinafter appear and be particularly defined in the claim.

The invention has been clearly illustrated in the accompanying drawings in which similar characters denote similar parts, and in which:

Figure 1 is a central longitudinal section of my improved device. Fig. 2 is a section on line 2-2 of Fig. 1 showing the parts in their operative positions. Fig. 3 is a view similar to Fig. 2 and illustrates the position of the parts when the rotation of the engine shaft is reversed by back-fire. Fig. 4 illustrates a modification.

Referring to the drawings, the numeral 10 denotes the shaft of a hydro-carbon engine which is journaled in a bearing 11 formed on the back plate 12 of a casing which is provided with ears 13 whereby the same may be firmly attached to the frame of the engine or of an automobile, as the case may be. The forward end of the shaft 10 carries a ratchet wheel 14 preferably keyed thereto, as shown in Fig. 2 and adapted to be engaged by a pawl 15 which is carried by a crank-operated member consisting substantially of a carrier or casing formed of a pair of adjacent sections 16 and 17 which are held together by screws or bolts 18. The

pawl 15 is pivoted on a stud 19, and its tail is bifurcated to receive between the branches and at the outer ends thereof a secondary pawl member 20 which is pivoted on a stud 21 carried by said pawl 15, a spring 22 serving to keep the relative position between the main pawl 15 and secondary pawl 20 normally the same, while at the same time it also serves to throw the main pawl 15, in its entirety, into engagement with the ratchet wheel 14, as will be readily understood.

In order to provide a substantial bearing for the pawl carrier or cage, the rear plate 17 has a hub 17' which is journaled in the back plate 12 as shown, and the front plate 16 has a trunnion 23 which is journaled in the bearing 24 formed on the front cover 25 of the inclosing casing. The latter consists in the present instance preferably of three parts, namely: the back plate 12, the cover plate 25 and the intermediate section 26, which latter has internal teeth 27 and is rigidly held on the back plate 12, and also in conjunction with the cover, by screws 28.

When now the trunnion 23 is rotated, as for instance by a crank indicated by C, clockwise, the cage or pawl carrier will become the operator to rotate the ratchet wheel in the direction of arrow a (see Fig. 2). It will also be understood that during such rotation the secondary pawl 20 will "click-by" the teeth 27 of the stationary casing ring 26, therefore leaving the engagement between the pawl 15 and the ratchet wheel 14 intact. Let it be supposed, however, that the engine back-fires, so that consequently the ratchet wheel is forced in the direction of arrow b (see Fig. 3) by the explosions in the cylinder, the cage or pawl carrier will naturally also be moved in that direction, but in that instance the secondary pawl 20 will catch against one of the stationary teeth 27 and be swung around this point of contact, therefore bringing it into the position shown in Fig. 3 where it will be seen that the secondary pawl 20 has become active as a lever depressing the tail of the main pawl 15 toward the center of the shaft and against the action of the spring 22 to bring its tooth-engaging portion out of the path of the ratchet teeth 14, whereupon any further backward rotation of the pawl carrier naturally comes, such total backward rotation of the pawl carrier being very small and extending only from the line X in Fig. 3 to that marked Y. It will also be

100

110

understood that just as soon as the pawl carrier is again rotated in the direction of arrow *a*, by the crank, the pawl 15 will again engage the ratchet teeth, as before. In brief, it will be understood that as long as the pawl carrier is rotated clockwise, the pawl 15 remains in active operation to turn the ratchet wheel 14, the stationary casing with its teeth 27 performing no function in this operation. On the other hand, said teeth will become effective in disengaging said pawl from the ratchet wheel as soon as the pawl carrier is rotated reversely, whether by the crank or by the backward rotation of the engine shaft.

In Fig. 1 the ratchet wheel 14 is illustrated as being disposed within the pawl carrier, and in order to hold the same against movement during the ordinary run of the engine, and also to hold a crank which may be attached thereto, in a certain position, I have provided means whereby the carrier is normally held stationary, these means comprising preferably a spring-actuated plunger 30, the end of which is adapted to enter an aperture 31 in the pawl carrier. The plunger 30 is attached to a button 32, the cross-pin 33 of which is normally seated in the recess 34 of the supporting hub, but it may be pulled out of the same and rotatably disposed on the supporting hub to prevent the engagement of the plunger 30 with the pawl carrier, in which condition the latter is free to be rotated without interference.

While, as above described, the mechanism can be organized as shown in Figs. 2 and 3, it will be evident that the ratchet wheel 14 will be rotated as long as the engine shaft 10 is operated. This means that when the pawl carrier is stationary, the ratchet wheel 14 will slide under or click-by the pawl 15. In order to avoid the noise which this construction entails, the organization may be made in the manner shown in Fig. 4, in which the engine shaft 10' is normally free from the pawl carrier 35, the construction of which is substantially the same as previously described, but the inner hub 36 of which is provided with clutch teeth 37 adapted to engage similar teeth 38 provided on the collar 39 which is carried by the engine shaft. A spring 40 surrounds the hub 36 of the pawl carrier and is seated in the recess 41 so as to push the carrier 35 toward the right or into the position shown in Fig. 4, in which position the clutch teeth are free from each other. In that case the

spring-operated retaining member 30 of Fig. 1 can now be replaced by a projecting lug 42 shown in Fig. 4, the spring 40 serving to retain the face of the carrier, or more particularly speaking a suitable recess therein, in engagement therewith, as will be readily understood.

When the device shown in Fig. 4 is to be operated by the crank *C*, an inward push in the direction of arrow *c* should be imparted to the crank, in which case the carrier will be shifted bodily toward the engine shaft to bring the clutch teeth into engagement, it being understood that the internal gear teeth 27 are of such width as to permit this sliding movement without passing out of the zone of the secondary member 20, the operation of which will remain precisely as previously described. As soon as the inward push on the crank is released, the parts will resume the positions shown in Fig. 4, leaving the entire cranking device idle.

Changes may be made in the general organization, as well as in the particular construction of my improved device without departing from the spirit of the invention, especially in the construction of the pawl carrier and its co-operative parts, and also in the manner whereby such pawl carrier may be normally held against rotation.

I claim:

The combination with an engine shaft, and a ratchet wheel secured thereto, of a crank-operated carrier comprising a pair of spaced side sections secured together, one side section having a rearwardly projecting hub, the other side section having a polygonal crank-receiving portion, a casing enclosing said carrier and having journal bearings for said hub and said trunnion respectively, internal gear teeth formed in said casing in lateral alignment with the space between said carrier-sections, a pawl pivoted intermediate its ends between said carrier-sections and adapted to engage said ratchet teeth, a dog pivoted on the outer end of said pawl and engaging said gear teeth, and a spring for normally holding said pawl and said dog in engagement with said ratchet wheel and the gear teeth, respectively.

In testimony whereof I affix my signature in presence of two witnesses.

JOHN G. WELSH.
